UNITED STATES PATENT OFFICE.

LUTE EUSEGER CAMPBELL, OF JOPLIN, MISSOURI, ASSIGNOR OF ONE-THIRD TO ALEXANDER F. DAVIS AND ONE-THIRD TO CLAUDE THORNTON, OF JOPLIN, MISSOURI.

NUT-LOCK.

No. 905,842.

Specification of Letters Patent.

Patented Dec. 8, 1908.

Application filed March 11, 1908. Serial No. 420,440.

To all whom it may concern:

Be it known that I, LUTE EUSEGER CAMPBELL, a citizen of the United States, residing at Joplin, in the county of Jasper and State 5 of Missouri, have invented a new and useful Nut-Lock, of which the following is a specification.

The invention relates to improvements in nut locks.

10 The object of the present invention is to improve the construction of nut locks, and to provide a simple, inexpensive and efficient one designed particularly for use on rail joints, and adapted to be readily applied to a 15 nut and capable of effectually preventing the same from accidentally unscrewing.

A further object of the invention is to provide a nut lock of this character, which may be readily disengaged from a nut, when it is 20 desired to remove the same from its bolt.

With these and other objects in view, the invention consists in the construction and novel combination of parts hereinafter fully described, illustrated in the accompanying 25 drawing, and pointed out in the claim here-to appended; it being understood that various changes in the form, proportion, size and minor details of construction, within the scope of the claim, may be resorted to without departing from the spirit or sacrificing any of the advantages of the invention.

In the drawing:—Figure 1 is a perspective view of a portion of a rail joint provided with a nut lock, constructed in accordance with 35 this invention. Fig. 2 is a transverse sectional view. Fig. 3 is a sectional view taken substantially on the line 3—3 of Fig. 2. Fig. 4 is a detail perspective view of the nut lock showing the same before the jaws are 40 bent.

Like numerals of reference designate corresponding parts in all the figures of the drawing.

1 designates a nut lock, which is stamped 45 or otherwise formed from sheet metal, and the said nut lock consists of a lower engaging body portion 2, side jaws 3 and an intermediate jaw 4. The intermediate and side jaws are formed by cutting or splitting the 50 metal at opposite sides of the median line of

the nut lock, the cuts or splits extending from the top of the nut lock and terminating short of the bottom of the same. The intermediate partially severed portion, which constitutes the jaw 4, is bent backward upon the 55 body portion 2 to provide a bolt receiving opening or recess 5.

The side jaws 3 are arranged at opposite sides of a bolt 6, as clearly illustrated in Fig. 3 of the drawing, and the lower edge 7 of the 60 body portion 2 of the nut lock engages the bottom flange or portion 8 of a fish plate 9, or other suitable stop.

The nut lock is applied to a bolt before the nut is screwed on the same, and after the 65 nut is screwed home, the upper ends of the side jaws are bent downwardly upon the upper edge of the nut, and the intermediate jaw is bent around the lower edge of the nut, the terminal of the lower jaw being located 70 at the front face of the nut and at the adjacent end of the bolt, as shown. The nut lock, by engaging the bottom flange or portion of the fish plate and the upper and lower edges of the nut, securely grip the latter, and 75 effectually prevent the same from accidentally rotating. The jaws are adapted to be readily bent out of engagement with the nut, when it is desired to unscrew the same. The nut lock besides being adapted for use 80 on rail joints, may be advantageously employed on various machines and structures subject to vibration.

Having thus fully described my invention, what I claim as new and desire to secure by 85 Letters Patent, is:—

The combination with a bolt and a nut, of a nut lock constructed of sheet metal and consisting of a body portion arranged at the inner face of the nut below the bolt and ex- 90 tended beyond the nut and having a straight lower edge for engaging the bottom flange or portion of a fish plate or other stop, and intermediate and side jaws connected with the top of the body portion, the intermediate 95 jaw being bent downwardly upon the outer face of the body portion to provide a bolt receiving space or recess between the side jaws and then horizontally to engage the lower edge of the nut and having its 100

terminal portion extended vertically and engaging the outer end of the bolt, and the side jaws being extended vertically at opposite sides of the bolt and having their upper terminals bent outward and engaging the upper edge of the nut.

5 In testimony, that I claim the foregoing as

my own, I have hereto affixed my signature in the presence of two witnesses.

LUTE EUSEGER CAMPBELL.
